UNITED STATES PATENT OFFICE.

ALEXIS B. PRIBIL, OF DETROIT, MICHIGAN, ASSIGNOR TO AUTOMATIC PLATEN PRESS COMPANY, OF NEW YORK, N. Y., A CORPORATION OF NEW JERSEY.

SHEET-MANIPULATING MECHANISM.

968,978.

Specification of Letters Patent. Patented Aug. 30, 1910.

Application filed October 12, 1908. Serial No. 457,209.

To all whom it may concern:

Be it known that I, ALEXIS B. PRIBIL, a citizen of the United States of America, and a resident of Detroit, Wayne county, Michigan, have invented certain new and useful Improvements in Sheet-Manipulating Mechanisms, of which the following is a specification.

This invention relates to improvements in sheet manipulating mechanisms and particularly refers to novel means for feeding and delivering sheets to the platen of a press of the type known as a job press, although it will appear and must be understood that my invention may be useful on other types of printing machines.

One object of my invention is to provide a feed gripper by means of which the paper may be fed to any desired position on the platen, so that by simply adjusting the stroke or motion of the feed grippers, the feed is accommodated to the job to be printed.

Another object is to so locate the gripping mechanisms that they take up but little room and are conveniently located for adjustments or repairs.

In the accompanying drawing I have shown my invention in somewhat diagrammatic form and as employed on a job press having a stationary platen, but this type of printing machine is to be taken as an illustration only for the purpose of this disclosure.

In the said drawings Figure 1 is a side elevation of a job press equipped with a sheet feeding and delivery mechanism embodying my invention at the moment of impression and with parts omitted and Fig. 2 is a detail view of parts of the adjusting means for the feed grippers.

In the drawing the numeral 1 indicates the frame of a job press, which supports the platen 2, in this instance stationary, and the stock 3 to be printed. 4 denotes a suitable receptacle for said stock, which latter may be fed forward by a follower 5 while 6 denotes diagrammatically a mechanism for separating or crowding the first sheet off the pile and into the bite of the grippers. The arrangement for supporting and handling the sheets by the members just referred to is shown here for the sake of completeness only and has otherwise no bearing on this invention.

55 The feeding grippers are denoted by the

numeral 7 and may be of any suitable construction and operated by any well known means in the art. The grippers are operated by means of arms 8 one on each side of the press pivoted on a shaft 13. The delivery grippers, also of any suitable construction are denoted by the numeral 9 and are mounted in and operated by arms 10, one on each side of the machine and pivoted on a shaft 11.

In the drawing the feed grippers are shown in full lines in their lowermost position when handling the largest size of sheet to be printed on this press, and in dotted line they are shown also in their uppermost position at the moment of taking a sheet from the pile irrespective of the size of said sheet. As stated above these feed grippers may be operated to feed a sheet to any position on the platen within predetermined limits. And in dotted lines at 12 the feed grippers are shown in their lowermost position when feeding a sheet of the smallest size to be printed by this press. In order to accomplish this object it is only necessary to change the location of the shaft 13 and to make such minor change in the operating mechanism as is needed to obtain the exact stroke of the feed grippers. The shaft 13 is oscillated by means of the gear 14 meshing with the rack 15 which latter operates in a pivoted guide 16 by means of the bell crank 17 pivoted at 18. The one arm of the bell crank carries a cam roll 19 coacting with the cam 20 on shaft 21 to which power is applied in any convenient form. The shaft 11 for the delivery grippers is also oscillated by means of a gear and rack 22 and 23 respectively. The rack 23 operates in a pivoted guide 24 and its lower end is pivoted to a lever 25 which in turn is pivoted at 26 and carries a cam roll 27 also coacting with the said cam 20. From this it will be seen, that as the shaft rotates the arms 8 and 10 operate the feed and delivery grippers respectively and in time as shown in the drawing, and as will be presently explained.

In order to change the stroke of the feed grippers 7 the following means are employed, and as they are alike on both sides of the machine the description of the means on the one side will be sufficient. The shaft 13 is carried in boxes 29 which slide in ways 30, and may be fastened in any position in

said ways by bolts 31 and clamping nuts 35 provided with hand wheels 32. The gear 14 is fastened on the one end of said shaft and the arms 8 are provided with slots 33 and clamped to the shaft 13 by nut 34 or other suitable means. Now, when the stroke of the grippers 7 is to be changed, the nuts 34 are loosened, the clamps 35 are loosened and the boxes 29 are moved to the desired position in the ways 30 and clamped there. Next the grippers 7 are adjusted in the desired position on the platen and then clamped to the shaft 13, and the arms 8 then assume a corresponding position as shown at 12 in dotted lines. It will be evident that as the shaft 13 is moved the rack 15 also must change its position and this new position is also indicated in dotted lines at 36.

From an examination of the drawing it will be clear that the angles between the uppermost position of the feed grippers and the several lowermost positions thereof vary but slightly due to the direction of the ways 30, hence the stroke of the rack 15 needs but little adjustment, and this latter is obtained by adjusting the internally threaded sleeve 37 on the bell crank 17. As will be seen the one arm of the bell crank ends in a right hand threaded shaft 38, while the rack 15 is pivoted to a left hand threaded shaft 39 and the length of the thus combined shafts 38 and 39 is adjusted by turning the sleeve 37, hence the stroke of the rack 15 is adjusted to suit the location of shaft 13. In practice the stroke of the arms 8 vary but a few degrees so this adjustment is easily accomplished.

The operation of the grippers will be clear from the drawing and is as follows. In the position shown in full lines of the grippers 7, said grippers are at the end of their downward stroke and dwell there while the impression is being taken, at the same time the delivery grippers 9 have moved toward the platen but do not finish this motion until the form member 40 commences to leave said platen. The delivery grippers then move to the top of the platen and dwell there long enough to seize the printed sheet.

Next the feed grippers move up simultaneously with the withdrawal of the printed sheet, and in their uppermost position the feed grippers dwell long enough to seize a fresh sheet, while the delivery grippers in the meantime have reached their extreme right position and deliver the sheet. The movement of delivery grippers to the right is somewhat faster than the upward stroke of the feed gripper, and the downward stroke of these latter is faster than the leftward movement of the delivery grippers in order that these two gripper mechanisms may be timed correctly to suit the length of time of the impression.

I claim.

1. The combination of a platen, a shaft, a feeding mechanism adapted to oscillate with said shaft and means for varying the stroke of the said mechanism by changing the location of the said shaft.

2. The combination of a platen, a feeding mechanism adapted to oscillate around a given center and means for changing the location of said center for varying the stroke of the said feeding mechanism.

3. The combination of a platen, a feeding mechanism adapted to move around a given center and means for operating the said feeding mechanism from one given position into other varying positions by changing the location of the said given center.

4. The combination of a platen, a gripper mechanism adapted to move around a given center and means for varying the operations of the said gripper mechanism by changing the location of the said given center.

5. The combination of a feeding gripper mechanism, arms supporting the same, means for oscillating said arms around a given center and means for varying the stroke of the said arms by changing their position with relation to the said center.

Signed at Hanover Pa. this 2nd day of October 1908:

ALEX. R. PRIBIL.
